Design No. 311

Des. 581

Johnson, Cox & Fuller of Troy N.Y.

Assignees of
James J. Dullery of Troy aforesaid.
Letters Patent Dated July 19th 1853.

To all whom it may concern:

Be it known that J. J. J. Dullery of Troy, in the County of Rensselaer, and State of New York have invented or produced a new and original design of Cook Stove, which I call the "Domestic Improved", and I do here by declare that the following is a full, clear and exact description of the same, reference being had to the annexed perspective drawing, making a part of this specification.

The design of my stove consists of the rosette A A A. arranged on the oven and fire doors B and C. and panel of the jamb D. also the rosette E. E. arranged on the front doors F. F. of the front plate G. and in the ornamental borderings (a, a) arranged on the jamb-plate and moulding of the hearth H. and in the ornaments (b, b) on the leg I.

Having thus described my new design of cook stove.

What I claim as new and desire to secure by letters patent is, the ornamental design and configuration of cook stove such as herein described and represented in the annexed drawing.
